UNITED STATES PATENT OFFICE.

RALPH S. WALKER, OF NIAGARA FALLS, NEW YORK.

PUMP.

1,100,796.

Specification of Letters Patent. Patented June 23, 1914.

Application filed November 25, 1912. Serial No. 733,327.

To all whom it may concern:

Be it known that I, RALPH S. WALKER, a citizen of the United States, residing at Niagara Falls, in the county of Niagara and State of New York, have invented new and useful Improvements in Pumps, of which the following is a specification.

My invention relates to pumps.

One object of my invention is to provide an improved construction of pump having a rotary piston.

In connection with such object, another object of the invention is to provide a slideable chamber-dividing valve plate operable through movement of the piston.

Still another object of the invention is to provide in connection with such a valve plate, wedge portions on the piston to act against the valve plate so as to slide or 20 actuate the same, and a further object of the invention is to provide means to guide said valve plate during its sliding movement.

The invention resides in the novel construction and arrangement and details of parts hereinafter described and illustrated in drawings accompanying this application, which are to be taken as a part hereof.

In said drawings the preferred embodiment of the invention is shown, and therein:

Figure 1 is a side elevation; Fig. 2 is a vertical central sectional view; Fig. 3 is a transverse sectional view on the line 3—3 of Fig. 2, and; Fig. 4 is a perspective view of the end wall or plate employed to close the pump cylinder.

Like reference characters designate like or similar parts throughout the several views of the drawings.

Referring specifically to the drawings, the pump cylinder may be provided in any suitable manner, but as shown consists of a hollow pump cylinder section generally designated 1, and comprising an end wall 2 and a side circumferential wall 3. The other end wall of the pump cylinder may be separate from casing 1 and in the nature of a plate 4 which may be attached to the wall 3

50 in any suitable manner, as by means of bolts 5 passing therethrough and in screw threaded openings in the wall 3.

The piston employed, comprises a head 6 which operates within the hollow portion 55 of the cylinder, as is obvious. Such piston head has connected thereto a shaft 7 which

extends through the wall 2 and may be enlarged at 8 and mounted in a bearing 9 thereat, provided on the end wall 2. The shaft 7 may be rotated or driven in either direction by suitable means so as to thereby drive or rotate the piston head 6. The piston head 6 as shown, is provided with inner and outer arcuate walls, and at its ends terminates in wedge shaped portions 10, by reason of the provision of inclined or curved cam walls 11.

Within the cylinder is mounted a slideable valve plate member 12, which in effect divides the chamber within the cylinder into two equal compartments or chambers. Suitable means is provided to guide the plate 12 in its movement and such means may consist of the lugs 13 which are formed integral with, and project inwardly from the end plate 4. It is to be noticed that such lugs 13 are distanced or spaced apart so as to provide a slot or space in which the plate 12 slides. It is also to be noted that the inner arcuate wall of the piston head 6 follows the contour, or bears against the periphery of the lugs 13. The valve plate 12 may be of any suitable construction, but in connection therewith I prefer to provide a plate 14 which is provided with an elongated slot 15 which receives a tenon 16 provided on the main portion of the plate 12. One or more cavities such as 17 may be provided in the tenon 16, and in such cavities are mounted coil springs 18 which tend to press the plate 14 into engagement with the inner face of the wall 3. Such yielding connection of the plate 14 will take up or reduce the wear of the valve plate to some extent. As stated, the valve plate 12 in effect, divides the chamber of the pump cylinder into 2 separate chambers or compartments. These compartments are each provided with one or more ports to which may lead pipes designated 19.

In operation the shaft 7 is driven, and accordingly the piston head 6 is driven. In its movement, the wedge portions according to the direction of rotation, wedge in between the inner face of the wall 3 and the plate 12, and thus force or slide the same in a direction transversely of the cylinder.

It is to be noted that as the valve plate slides, that it bears against the wall 11 opposite to that of the wedge portion effecting the sliding movement of the valve plate. It will thus be seen that practically at all

times, the valve plate bears against both walls 11 of the piston head 6, thereby forming an effective closure between the two chambers provided on opposite sides of the 5 valve plate 12. It will be obvious that the fluid or material to be pumped, is pumped in through certain of the openings 18 and out through other of the openings. It is to be noted that I have provided an exceedingly simple construction of pump, one employing few parts, and one which may be manufactured at a minimum cost.

As merely the preferred embodiment of the invention has been shown, and changes 15 in the details of construction thereof may be resorted to, it is to be understood that such changes are reserved providing they fall within the spirit and scope of the appended claims.

20 Having thus described my invention, what I claim and desire to secure by Letters Patent is:—

1. In a pump, a stationary cylinder, plate means slidable within said cylinder, a piston 25 rotatable in said cylinder coöperating with said plate means to provide within the cylinder a plurality of chambers, inlet and outlet means for the chambers, said piston engageable with said plate means during rotation to slide the plate means.

2. In a pump, a stationary cylinder, plate means slidable within said cylinder transversely thereof, a piston rotatable in said cylinder extending partly around the same coöperating with said plate to provide within the cylinder a plurality of chambers, said cylinder having a wall extending at right angles to the axis of said piston, said wall provided with ports for the chambers, said 35 piston engageable with said plate means during rotation to slide the plate means.

3. In a pump, a stationary cylinder, plate means slidable within said cylinder, a piston 45 rotatable in said cylinder coöperating with said plate means to provide within the cylinder a plurality of chambers, inlet and outlet means for the chambers, said piston extending partly around the cylinder engaging the said plate means at opposite ends to 50 continuously slide the plate means during rotation of the piston.

4. In a pump, a stationary cylinder, plate

means slidable within said cylinder, a piston 55 rotatable in said cylinder coöperating with said plate means to provide within the cylinder a plurality of chambers, inlet and outlet means for the chambers, said piston extending partly around the cylinder and provided at opposite ends with cam faces, said cam faces engaging said plate means at opposite ends to continuously slide the plate means during rotation of the piston.

5. In a pump, a stationary cylinder, plate means slidable within said cylinder, a piston 65 rotatable in said cylinder coöperating with said plate means to provide within the cylinder a plurality of chambers, inlet and outlet means for the chambers, said piston extending partly around the cylinder having inner and outer walls and similar cam end 70 walls, plate means engaged at opposite ends by said cam walls to continuously slide the plate means, said plate means being of an extent transversely of the cylinder the same as the distance from the intersection of one 75 cam face with the other wall of the piston and the intersection of the other cam face with the inner wall of the piston.

6. In a pump, a stationary cylinder, plate means slidable within said cylinder, a piston 80 rotatable in said cylinder coöperating with said plate means to provide within the cylinder a plurality of chambers, said cylinder having an annular wall and side walls, one of said side walls being removable and 85 provided with guide lugs, plate means slideable between and guided by said lugs, said piston extending partly around the cylinder having inner and outer walls and similar end cam walls, said plate means engaged at 90 opposite faces by said cam walls to continuously slide the plate means, said plate means being of an extent transversely of the cylinder the same as the distance from the intersection of one cam face with the outer 95 wall of the piston and the intersection of the other cam face with the inner wall of the piston, and one of said side walls provided with ports for the cylinder.
